UNITED STATES PATENT OFFICE.

EDMUND PELOWITZ, OF WEST ORANGE, NEW JERSEY.

VAPORIZER FOR INTERNAL-COMBUSTION ENGINES.

1,375,011.

Specification of Letters Patent. Patented Apr. 19, 1921.

Application filed April 22, 1919. Serial No. 291,869.

To all whom it may concern:

Be it known that I, EDMUND PELOWITZ, a citizen of the United States, residing at West Orange, in the county of Essex and State of New Jersey, have invented certain new and useful Improvements in Vaporizers for Internal-Combustion Engines; and I do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in fuel-service devices or apparatus for use with internal combustion engines, such as are ordinarily employed for operating automobiles and similar vehicles; and, the present invention has reference, more particularly, to an auxiliary device in the form of a combined gasolene-saver, primer and carbon-remover, which is ordinarily mounted upon the tubular stem with which the steering wheel of the vehicle is used, the device being under the control of the operator seated in the vehicle, and being further connected with and coöperating with the intake and exhaust-manifolds of the engine for the purposes to be presently set forth.

The invention has for its principal object to provide a novel and simply constructed device or attachment for power-driven vehicles which is constructed and operated in such a manner, that the device may be used as a primer for feeding a quantity of gasolene into the intake-manifold of the engine, so as to facilitate and produce a quick-starting of the engine when the latter is chilled, especially in cold weather; and, furthermore, when the engine is running to conduct and add to the explosive mixture coming from the carbureter into the intake-manifold, a quantity of pre-heated air, so as to provide a more highly and readily explosive mixture.

The invention has for its further object to provide a device or apparatus which, at other times, may be used for conducting water by way of the intake manifold into the cylinder or cylinders of the engine for the removal of carbon, and which device may be used for producing vapor and pass-

ing the same into the cylinders of the engine, which will prevent the formation of the carbon therein.

A further object of the present invention is to provide in connection with a device or apparatus, for the purposes above stated, a receiver or vessel provided with a valve-device under control of the operator and easily manipulated, so that the device can be used whenever necessary, or may be entirely shut off from coöperation with the intake manifold, if desired.

The invention has for another object, the provision of a novel and simply-constructed gasket adapted to be located between the outlet from the carbureter and the inlet-member to the intake-manifold, said gasket having a duct and means for the connection therewith of a tubular element leading from the above-stated receiver or vessel.

Other objects of the present invention not at this time more particularly enumerated will be clearly understood from the following detailed description of the present invention.

With the various objects of the present invention in view, the said invention consists, primarily, in the novel apparatus or device, adapted for use as a combined gasolene saver, primer, carbon-remover, or vaporizer for internal combustion engines; and, the invention consists, furthermore, in the novel arrangements and combinations of the several devices and parts, as well as in the details of the construction of the said parts, all of which will be more fully described in the following specification, and then finally embodied in the clauses of the claim which are appended to and which form an essential part of the said specification.

The invention is clearly illustrated in the accompanying drawings, in which:—

Figure 1 is a view of a portion of an internal combustion engine and its intake and exhaust manifolds, with a portion of the steering means of the vehicle being also illustrated, said view showing in connection therewith and attached to the usual tubular member in which the steering rod or stem is incased, a device or apparatus embodying the principles of the present invention connected with the manifolds of the engine.

Fig. 2 is a vertical sectional representa-

tion of the said attachment, said view being made on an enlarged scale.

Fig. 3 is an enlarged side view of the gasket to be located between the outlet of the carbureter and the inlet-member of the intake-manifold; and Fig. 4 is a transverse sectional representation of the same, said section being taken on line 4—4 in said Fig. 3.

10 Fig. 5 is a detail vertical section, also made on an enlarged scale, said section being taken on line 5—5 in said Fig. 1.

Similar characters of reference are employed in the said above described views, 15 to indicate corresponding parts.

Referring now to the several figures of the drawings, the reference-character 1 indicates a fragmentary portion of the casing of an internal combustion engine, 2 is 20 the intake-manifold of the same provided with the inlet-member 3 which is flanged, as at 4, and 5 is the exhaust manifold, the manifolds being secured upon one side of the casing 1 by means of the clamps or 25 tightening clips 6, and the studs 7 and nuts 8, in any usual manner.

The reference-character 9 indicates the usual carbureter formed with an outlet or discharge-member 10 which is also flanged, 30 as at 11. Between the said flanges 4 and 11 is disposed a correspondingly formed gasket 12, see more particularly Figs. 3 and 4 of the drawings, said gasket being made of any suitable material serving as a proper 35 packing at the connection or joint between the members 3 and 10. Bolts 13 and nuts 14 are employed, as will be evident from an inspection of Fig. 1 of the drawings, for securing these parts in their assembled relation. The said gasket 12 is provided with the usual and centrally disposed open part 40 15 which corresponds to the interior duct- portions of said members 3 and 10, and in communication with said open part 15 and 45 leading to the peripheral edge of the gasket is a suitably formed inlet-duct 16, the gasket upon said edge and at that point having a tubular enlargement or nipple, as 17, which is externally screw-threaded, as at 50 18, for the attachment thereto of a tubular union 19 mounted upon the end of a piece of piping or flexible tubing 20.

The hereinabove mentioned device or attachment which may be used either as a 55 primer, a hot-air mixer, a vaporizer, or the like, is illustrated more particularly in Fig. 2 of the drawings, and the same consists, essentially, of a cup-shaped body 21, the upper open portion 22 of which is internally 60 screw-threaded, as at 23, for the reception of the screw-threaded flange 25 of a closing member or cap 24. The central portion of this closing member is made with an internally screw-threaded hole 26 into which is 65 screwed an adjusting screw 27 formed with

a longitudinally extending tubular duct 28, which terminates at a point near the lower end-portion of said screw in a laterally extending outlet-duct or perforation, as 29. At its lower portion, the said cup-shaped 70 body 21 has a suitably formed projection or extension, as 30, to which is secured by means of a screw or tap-bolt 31, or in any other suitable manner, a clamping means 32 adapted to embrace and to be secured 75 in a clamped position upon a portion of the tubular member 33 which serves as a casing for the usual steering rod or stem of the motor-driven vehicle, all of which is clearly indicated in Fig. 1 of the drawings. The 80 position of the said cup-shaped body 21 with relation to said member 33 is preferably that shown in Figs. 1 and 2. Referring now once more to said Fig. 2, it will be seen that the said body 21 is formed 85 with two tubular projections or extensions 34 and 35, both of which communicate with the lower interior part of the said body 21. The upper projection or extension 34 is interiorly screw-threaded, as at 36, having 90 screwed therein a closing cap 37 which is formed with a guide-duct 38. The lower projection or extension 35 is also interiorly screw-threaded, as at 39, for the screwing therein of a tubular union 40, mounted upon 95 the other end of the previously mentioned piping or flexible tubing 20.

The inner portion of the duct, with which the said projection or extension 35 is provided, is made with a valve-seat, as 41, upon which is normally seated a cone-shaped valve-member 42 having a stem 43 which extends in an upward direction into and through the guide-duct 38, said stem 43 projecting from the closing cap 37 and being 100 provided upon its free end with an attaching means or eye 44. Encircling the said stem 43, between the said cap 37 and the valve-member 42 is a coiled spring 45, for normally seating said valve-member upon 105 the valve-seat 41, as will be evident. Suitably attached to said eye 44 is a pull-member 46, in the form of a wire-rod or a flexible connector, the upper end-portion of which may be made in such suitable manner, 110 that it can be detachably connected with a holding hook, as 47, or other suitable fastening means, secured to and extending from the side of the member or casing 33, within 115 easy reach of the operator seated in the vehicle.

At a point near the top of said cup-shaped body 21, and upon the outer side thereof, is a chambered member 48, the interior of which is in communication with the interior of said body 21 by means of a perforation or opening, as 49. The lower wall of said chambered member 48 is also formed with an internally screw-threaded inlet, as 50, with which is connected a tubular union 120 125 130

51, suitably mounted upon the one end of a pipe or other tubular flexible connection 52, said pipe or connection 52 having fitted upon its other end an air-inlet receiver 53, which is usually cone-shaped and is adapted to be fitted over and above the exhaust-manifold 5, substantially as indicated in Fig. 5 of the drawings. The upper end of the said receiver 53 has an outlet-portion 54 with which the said pipe or connection 52 is suitably connected. Upon its lower portion, the said receiver has an arm or extension 55 of sufficient length, so as to extend down the outer side of the exhaust-manifold 5, and to be clamped in a fixed relation against the intake-manifold 2, by means of the tightening clips 6, or any other suitable fastening means.

While in the foregoing I have described one general arrangement and construction of devices and parts comprising one embodiment of combined gasolene saver, primer, carbon-remover, air-heater, and vaporizer, I am fully aware that changes may be made in the general arrangements and combinations of the several devices and parts, as well as in the details of the construction of the said parts, without departing from the scope of the present invention as set forth in the said specification, and as defined in the clauses of the claim which are appended to the said specification. Hence, I do not limit my present invention to the exact arrangements and combinations of the several devices and parts as described in the foregoing specification, nor do I confine myself to the exact details of the construction of the said parts, as illustrated in the accompanying drawings.

40 The manipulation and operation of the device or attachment briefly is as follows:—

When the device or attachment is to be used as a priming means, all that is necessary, the parts of the device being in their relative positions shown in Fig. 2 of the drawings, is to unscrew the closing member or cap 24, and fill the chamber of the body 21 with a charge of gasolene. The cap 24 may then be screwed back into place. By means of the pull-member 46 and the stem 43, the valve-member 42, against the normal closing action of the spring 45, is removed from the valve-seat 41, thus allowing the gasolene to flow into and down the pipe or tubing 20, into and through the gasket 12, and thence into the inlet member of the intake-manifold 2, to be sucked, with the usual cranking action or other starting means into the cylinders, where it is easily and quickly exploded in any of the usual manners. The gasolene-charges may be repeated as often as may be necessary, although one charge will usually suffice. After the engine has been started, the valve-body or member 42 is returned automatically upon its seat by re-

leasing the pull-member 46, as will be evident.

When it is desired to add, from time to time, heated air to the fuel-mixture entering from the carburetor into the inlet-member 70 of the intake-manifold 2, during operation or running of the engine, the valve-member 42 is similarly removed from the valve-seat 41 by manipulation of the pull-member 46. The hot air above the exhaust-manifold is 75 thus sucked into the cone-shaped receiver 53, through the pipe or tubing 52, into the chambered body 21, and thence therefrom into and through the pipe or tubing 20 and the gasket 12 into the inlet-member of the 80 intake-manifold 2, to be mixed with the highly explosive gaseous fuel-mixture coming from the carburetor, as will be understood. As soon as the engine is running 85 smoothly, the pull-member 46 is again released, so that the valve-member will automatically seat itself upon the valve-seat, and the engine will be charged solely from the carburetor.

When the attachment or device is to be 90 used for flushing out the cylinders with water for the removal of carbon, or, when it is to be employed as a vaporizer or humidifier to force a vapor into the engine for the purpose of preventing the formation of 95 carbon, the adjusting screw 27, with which the closing member or cap 24 of the cup-shaped body 21 is provided, is screwed farther down into a position that the laterally extending outlet duct or perforation 29, 100 which is in communication with the duct 28, will be below the lower surface-portion of the said closing member or cap 24. A tube or pipe, leading from a tank or reservoir containing water, (both of which are, however, not shown here,) is then secured upon and over the open end-portion of said adjusting screw 27. The engine having been started, the valve-member 42 is removed from the valve-seat 41, by means of the pull-member 46, in the same manner as herein-before stated, the water entering through the duct 28 in a very thin stream into the chamber of the body 21 and the unseated valve-member 42 into and through the pipe 115 or tubing 20 into and through the gasket 12, and thence by means of the intake manifold into the cylinder or cylinders of the engine. During the continuous running of the engine, the pull-member 46 may be hooked over the hook 47 so as to unseat the valve-member 42. Heated air from above the manifold, see Fig. 5, is drawn into the body 21, producing a vapor which, in the manner just described, is sucked into the engine-cylinder or cylinders, thus producing a more effective operation of the motor with the best results, so as to increase the power of the engine, producing economy in fuel-consumption, and at the same time preventing 120 125 130

the deposits of carbon upon the pistons and other parts of the engine.

I claim:

1. An attachment for internal combustion engines adapted for use as a primer, fuel-heater, economizer, or vaporizer, comprising a chambered body, a chambered extension located upon the outer side of said body, said chambered extension being provided with an inlet, said body being also provided with an outlet having a valve-seat, a valve-body normally located upon said valve-seat, a clamping means connected with said body for its attachment to the steering-rod casing of a vehicle, and a conveying means comprising a tubular conveying duct connected at one end to said outlet, and a gasket at the other end of said duct for attachment between the outlet portion of a carbureter and the inlet-member of the intake-manifold of the engine, said gasket having a conveying duct-portion in communication with the interior of said conveying duct and the said carbureter and manifold-members.
2. An attachment for internal combustion engines adapted for use as a primer, fuel-heater, economizer, or vaporizer, comprising a chambered body, means for attaching said body in a convenient location upon a motor-vehicle, a chambered extension located upon the outer side of said body, said chambered extension being provided with an inlet, said body being also provided with oppositely located tubular extensions, a valve-seat in one of said extensions, a valve-body normally located upon said valve-seat, a closing cap mounted in the other extension, said cap having a guide-duct, a stem connected with said valve-body, said stem extending into and through said guide-duct, means connected with the free end of said stem for actuating the same to lift the valve-body from said valve-seat, a coiled spring encircling said stem, and a conveying means connected with the valve-seat-provided extension and adapted to be connected with a part of the engine.
3. An attachment for internal combustion engines adapted for use as a primer, fuel-heater, economizer, or vaporizer, comprising a chambered body, means for attaching said body in a convenient location upon a motor-vehicle, said body being provided with oppositely located tubular extensions, a valve seat in one of said extensions, a valve-body normally located upon said valve-seat, a closing cap mounted in the other extension, said cap having a guide-duct, a stem connected with said valve-body, said stem extending into and through said guide-duct, means connected with the free end of said stem for actuating the same to lift the valve-body from said valve-seat, a coiled spring encircling said stem, and a conveying means connected with the valve-seat-provided extension comprising a tubular conveying duct connected at one end with said extension, and a gasket at the other end of said duct for attachment between the outlet portion of a carbureter and the inlet-member of the intake-manifold of the engine, said gasket having a conveying duct-portion in communication with the interior of said conveying duct and the said carbureter and manifold-members.
4. An attachment for internal combustion engines adapted for use as a primer, fuel-heater, economizer, or vaporizer, comprising a main chambered body, means for attaching said body in a convenient location upon a motor-vehicle, a chambered extension located upon the outer side of said body and having a means of communication with the interior of said body, said chambered extension being provided with an inlet, a tubular conveying duct connected with said inlet, a hot-air-receiver upon the free end of said duct, said main body being provided with oppositely located tubular extensions, a valve-seat in one of said extensions, a valve-body normally located upon said valve-seat, a closing cap mounted in the other extension, said cap having a guide-duct, a stem connected with said valve-body, said stem extending into and through said guide-duct, means connected with the free end of said stem for actuating the same to lift the valve-body from said valve-seat, a coiled spring encircling said stem, and a conveying means connected with the valve-seat-provided extension and adapted to be connected with a part of the engine.
5. An attachment for internal combustion engines adapted for use as a primer, fuel-heater, economizer, or vaporizer, comprising a main chambered body, means for attaching said body in a convenient location upon a motor-vehicle, a chambered extension located upon the outer side of said body and having a means of communication with the interior of said body, said chambered extension being provided with an inlet, a tubular conveying duct connected with said inlet, a hot-air-receiver upon the free end of said duct, said main body being provided with oppositely located tubular extensions, a valve-seat in one of said extensions, a valve-body normally located upon said valve-seat, a closing cap mounted in the other extension, said cap having a guide-duct, a stem connected with said valve-body, said stem extending into and through said guide-duct, means connected with the free end of said stem for actuating the same to lift the valve-body from said valve-seat, a coiled spring encircling said stem, and a conveying means connected with the valve-seat-provided extension, comprising a tubular conveying duct connected at one end with said extension, and a gasket at the other end of said duct for attachment between the outlet portion of a carbureter and the inlet-member of the intake-manifold of the engine.

of a carburetor and the inlet-member of the intake-manifold of the engine, said gasket having a conveying duct-portion in communication with the interior of said conveying duct and the said carburetor and manifold-members.

6. An attachment for internal combustion engines adapted for use as a primer, fuel-heater, economizer, or vaporizer, comprising a main chambered body, means for attaching said body in a convenient location upon a motor-vehicle, said body being provided with an upper open portion, a perforated cap mounted so as to close said opening, a screw 10 adjustably disposed in the perforation of said cap, said screw having a longitudinally extending duct terminating in a horizontally disposed duct-portion at a point near the lower end of said screw, and said main body being formed with an inlet and an outlet.

7. An attachment for internal combustion engines adapted for use as a primer, fuel-heater, economizer, or vaporizer, comprising a main chambered body, means for attaching said body in a convenient location upon a motor-vehicle, said body being provided with an upper open portion, a perforated cap mounted so as to close said opening, a screw adjustably disposed in the perforation of said cap, said screw having a longitudinally extending duct terminating in a horizontally disposed duct-portion at a point near the lower end of said screw, and 20 said main body being formed with an inlet and an outlet, said outlet having a valve-seat, a valve-body normally located upon said valve-seat, and a conveying means connected with said outlet and adapted to be connected with a part of the engine.

8. An attachment for internal combustion engines adapted for use as a primer, fuel-heater, economizer, or vaporizer, comprising a main chambered body, means for attaching said body in a convenient location upon a motor-vehicle, said body being provided with an upper open portion, a perforated cap mounted so as to close said opening, a screw adjustably disposed in the perforation of said cap, said screw having a longitudinally extending duct terminating in a horizontally disposed duct-portion at a point near the lower end of said screw, and said main body being formed with an inlet 40 and an outlet, said outlet having a valve-seat, a valve-body normally located upon said valve-seat, and a conveying means comprising a tubular conveying duct connected at one end to said outlet, and a gasket at the 50 other end of said duct for attachment between the outlet portion of a carburetor and the inlet-member of the intake-manifold of the engine, said gasket having a conveying duct-portion in communication with the in-

terior of said conveying duct and the said carburetor and manifold-members.

9. An attachment for internal combustion engines adapted for use as a primer, fuel-heater, economizer, or vaporizer, comprising a main chambered body, means for attaching said body in a convenient location upon a motor-vehicle, said body being provided with an upper open portion, a perforated cap mounted so as to close said opening, a screw adjustably disposed in the perforation of said cap, said screw having a longitudinally extending duct terminating in a horizontally disposed duct-portion at a point near the lower end of said screw, a chambered extension located upon the outer side of said body and having a means of communication with the interior of said main body, said chambered extension being provided with an inlet, a tubular conveying duct connected with said inlet, a hot-air-receiver upon the free end of said duct, said main body being formed also with an outlet, and a means of communication between said outlet and a part of the engine.

10. An attachment for internal combustion engines adapted for use as a primer, fuel-heater, economizer, or vaporizer, comprising a main chambered body, means for attaching said body in a convenient location upon a motor-vehicle, said body being provided with an upper open portion, a perforated cap mounted so as to close said opening, a screw adjustably disposed in the perforation of said cap, said screw having a longitudinally extending duct terminating in a horizontally disposed duct-portion at a point near the lower end of said screw, a chambered extension located upon the outer side of said body and having a means of communication with the interior of said main body, said chambered extension being provided with an inlet, a tubular conveying duct connected with said inlet, a hot-air-receiver upon the free end of said duct, said main body being formed also with an outlet, 90 said main body having an outlet provided with a valve-seat, a valve-body normally located upon said valve-seat, and a conveying means connected with said outlet and adapted to be connected with a part of the engine.

11. An attachment for internal combustion engines adapted for use as a primer, fuel-heater, economizer, or vaporizer, comprising a main chambered body, means for attaching said body in a convenient location upon a motor-vehicle, said body being provided with an upper open portion, a perforated cap mounted so as to close said opening, a screw adjustably disposed in the perforation of said cap, said screw having a longitudinally extending duct terminating in a horizontally disposed duct-

portion at a point near the lower end of said screw, a chambered extension located upon the outer side of said body and having a means of communication with the interior of said main body, said chambered extension being provided with an inlet, a tubular conveying duct connected with said inlet, a hot-air-receiver upon the free end of said duct, said main body being formed also 10 with an outlet, said main body having an outlet provided with a valve-seat, a valve-body normally located upon said valve-seat, and a conveying means connected with said outlet and adapted to be connected with a 15 part of the engine, comprising a tubular conveying duct connected at one end to said

outlet, and a gasket at the other end of said duct for attachment between the outlet portion of a carbureter and the inlet-member of the intake-manifold of the engine, said gasket having a conveying duct-portion in communication with the interior of said conveying duct and the said carbureter and manifold-members.

In testimony that I claim the invention 25 set forth above I have hereunto set my hand this 19th day of April, 1919.

EDMUND PELTOWITZ.
